ALFRED SANDERS, OF PENN YAN, NEW YORK.

Letters Patent No. 81,689, dated September 1, 1868.

IMPROVED CAR-COUPING.

The Schedule referred to in these Letters Patent and making part of the same.

TO ALL WHOM IT MAY CONCERN:

Be it known that I, ALFRED SANDERS, of Penn Yan, in the county of Yates, and State of New York, have invented certain new and useful Improvements in Car-Couplings; and I do hereby declare that the following is a full and exact description thereof, reference being had to the accompanying drawings, making part of this specification.

Figure 1 is a perspective view of a draw-head provided with my improvement.

Figure 2, a longitudinal section of the same.

Like letters of reference indicate corresponding parts in both figures.

My invention consists in combining, with a spring-lever operated by an outside crank-work, a horizontal fastening of the link or shackle, produced by lugs secured thereto with a pin passing through, the whole arranged in such manner that while the pin simply serves to hold the link in place in coupling, the strain or draught, under motion, is applied to the lever itself, and not the pin.

In the drawings, A indicates the ordinary draw-head, and B the link or shackle.

A lever, C, is pivoted at *a*, vertically, in the draw-head, with a spiral spring, *b*, drawing back on the upper arm, which closes the lower arm against a stop or shoulder, *c*. A cam-rod, *d*, rests in a groove, *f*, in the back of the lever, having a horizontal shaft, *g*, extending outward, with crank *h* on the end. By turning this crank forward, the lever is thrown back, as indicated by red lines, fig. 2.

If desirable, the upper arm of lever C may have a ratchet formed theron, and the cam-rod *d* may be in the form of a pawl, which catches in the ratchet-teeth, and thereby holds the lever open to uncouple in switching off a train.

The link or shackle has vertical side-lugs, *i i*, attached thereto near the ends, with oblong openings, *k k*, therein, in which rests a small pin, *l*, passing horizontally through the draw-head.

The operation is as follows:

The lever C is first thrown back sufficiently for the link to hook around it, and then drawn forward, so as to allow the pin *l* to pass through and engage with lugs *i i*. In this condition the link is fast, either to strike back into the next draw-head to couple, or to move forward and sustain the draught in the motion of the train. In striking back to couple, the slight pin *l* is sufficient to hold the link in place, but in the opposite motion, under draught, the oblong openings *k k* in the lugs allow the link to draw forward sufficiently to transfer the strain upon the lever C, thereby relieving the pin from all strain.

To uncouple, the pin is withdrawn, and the lever thrown back, by simply turning the crank, and without the operator going between the cars.

This double attachment of the link to the lever and pin always keeps it extended and stiff, in proper position to couple, and the transferring of the strain from the pin to the lever insures the proper degree of strength.

I prefer to form a suitable space at the bottom of each draw-head, to receive a loose link or shackle lying out of the way of the action of the parts, but serving as a reserve at any time in use.

What I claim as my invention, and desire to secure by Letters Patent, is—

The combination of the side-lugs *i i*, oblong openings *k k*, and pins *l*, with the spring-lever C, and cam-rod *d g h*, the whole so arranged as to form a double fastening, and allow the strain to be transferred from the pin to the lever, as herein set forth.

In witness whereof, I have hereunto signed my name in the presence of two subscribing witnesses.

ALFRED SANDERS.
